UNITED STATES PATENT OFFICE.

WILLIAM SOPER, OF READING, ENGLAND.

BREECH-LOADING FIRE-ARM.

SPECIFICATION forming part of Letters Patent No. 252,271, dated January 10, 1882.

Application filed September 27, 1880. (No model.) Patented in England August 29, 1879.

To all whom it may concern:

Be it known that I, WILLIAM SOPER, of Reading, England, gun-manufacturer, have invented new and useful Improvements in Breech-Loading and other Fire-Arms, (for which I have obtained a patent in Great Britain, No. 3,480, bearing date August 29, 1879,) of which the following is a specification, reference being had to the accompanying drawings.

- 10 My invention relates to improvements in fire-arms, and comprises a peculiar combination of parts, whereby the opening of the breech, the cocking of the piece, and the extraction of the empty cartridge-shell are simultaneously effected by one movement of the hand upon an arm or lever at the side of the gun without materially changing the position in which the same is held when being fired.
- 15 In the drawings, Figure 1 is a longitudinal section on the line x x , Fig. 6, of the breech mechanism of a fire-arm constructed according to the first part of my invention. Figs. 2 and 3 are similar views of the said breech mechanism on the lines x' x' and x^2 x^2 on the same figure; and Fig. 4 is an under side view of a portion of the same. Fig. 5 is a side view of the breech of the said fire-arm. Figs. 6 and 6^a are transverse sections of the said breech mechanism on the lines y y y' y' , Fig. 1. Fig. 7 is a 20 transverse section of the breech-shoe on the line y^2 y^2 , Fig. 1, showing the rear face of the aperture in which the breech-block slides; and Fig. 8 is a transverse section of the said breech-shoe on the line y^3 y^3 , Fig. 1, looking toward 25 the front end of the gun. Fig. 9 is a front view. Fig. 10 is a rear or back view, and Fig. 11, a longitudinal section of the breech-block of my improved fire-arm. Fig. 12 is a rear view of the breech tumbler detached, and 30 Fig. 13 is a longitudinal section of the said breech-tumbler. Fig. 14 is a longitudinal section similar to Fig. 2, showing slight modifications in the construction of the breech mechanism of my improved fire arm; and Fig. 15 35 is a longitudinal section of the said breech mechanism on the line z z , Fig. 6, showing the said modifications; and Fig. 16 is a side view of a portion of the same detached.

Like letters indicate the same parts throughout the drawings.

a represents the barrel; b , the stock; c , the breech-shoe; d , the breech-block; e , the trig-

ger-plate; f , the cock or hammer; g , the main-spring; h , the main trigger; i , the striker or firing-pin; j , the extractor; k , the breech-tumbler, and l the operating-lever. The remaining parts are hereinafter described.

The invention is more especially designed with the view to secure the advantages of the aforesaid simultaneous operations more conveniently and with a smaller cost than is practicable with the mechanism I have heretofore employed for the purpose.

My invention is carried into practice as follows—that is to say: The mechanism is chiefly 65 inclosed within the metal breech block or shoe c , which extends downward at the rear of the barrel a . The breech-block d slides vertically within this shoe, and is in its highest position when the piece is ready to be fired, the said 70 breech-block being caused to descend when the exploded cartridge-shell has to be removed and a fresh one inserted. I arrange the said breech-block d to slide in such a manner that its upper surface, d' , will project above the 75 level surface of the breech-shoe c , so as to prevent the escape of gas in a rearward direction from a defective cartridge.

According to one form of my said improvements a slot or groove, d^2 , is formed in each 80 side of the breech-block, near the lower end of the same, the said grooves being cut at right angles to the line of motion of the said breech-block. Each of the said grooves is adapted to receive a stud or pin, k' , on the end of an 85 arm, k^2 , of the tumbler k . By reason of this arrangement of the said grooves in relation to the arms k^2 the said arms k^2 will depress or elevate the breech-block d by direct pressure, when the aforesaid lever l , in connection with 90 the tumbler k , is depressed or raised. The said breech-tumbler k is constructed and arranged as follows—that is to say: The two arms k^2 are connected at their lower end by a tubular transverse part, k^3 , which is formed 95 solidly or in one piece with them, as shown in Figs. 12 and 13, and keyed or otherwise secured upon the spindle l' in such a manner that the arms k^2 participate in any motion imparted to the latter. The said spindle l' extends through the breech-shoe c at right angles to the axis of the barrel. One of its ends outside the said shoe carries the operating-lever l , which is formed on or attached to the 100

said spindle, and extends rearward to a convenient position to be raised and depressed by the hand of the person using the fire-arm. The spindle l' may be square and fitted to a 5 square hole in the tumbler k , or I may form on the said spindle two wings or projections, which fit into a corresponding slot provided for the purpose in the tumbler, or the latter may be secured to the spindle in any other 10 suitable manner. I prefer, however, to form a flat or elongated hole in the part k^3 of the 15 said tumbler, and to form that part of the spindle which passes through the same of corresponding shape, as shown in the drawings, and I secure the said spindle in the tumbler k by a set-screw, k^* , which by a half-turn will release the spindle and allow it to be withdrawn from the said tumbler. The portions 20 of the said spindle which extend through the breech-shoe are so fitted in the same as to permit its being freely turned by the main or operating lever l . A short arm, k^4 , also forming part of the breech-tumbler, extends downward from the part k^3 , and carries a stud or 25 pin, k^5 , which enters a slot, m' , in a connecting-rod, m , whose other end is attached to the cock or hammer f in such a manner that when the tumbler k is operated to depress the breech-block the said cock or hammer will be drawn 30 back. The slot m' in the connecting-rod m is provided in order that when the cock has been drawn back to full or half cock the breech-block d may be returned to its upper position behind the breech without operating the said 35 cock.

In Fig. 1 I have shown the connecting-rod m attached to the cock f by forming in the body of the latter a suitably-shaped recess to receive the end of the said connecting-rod 40 link or swivel, in a somewhat similar manner to that usually employed in cocks or tumblers for the fixing of an ordinary swivel, and on the end of the said connecting-rod I form suitable pins, horns, or projections, m^2 , to fit in the 45 said recess.

Upon the aforesaid tubular part k^3 of the breech-tumbler k , I provide a spur or projection, k^6 , which is so arranged that when the breech-block d has been depressed to the required distance the said spur will come in contact with the cartridge-extractor j , and impart to the latter the necessary movement to draw out the cartridge.

I provide at the lower end of the cartridge-extractor j a short arm or projection, j' , with which the breech-block of the said connecting-rod is arranged to come in contact at the proper moment to give to the said extractor a sudden sharp movement or jerk, whereby the cartridge-shell, which has been partially withdrawn, as above described, is completely ejected from the gun. In order to facilitate the return of the said extractor to its normal position, the recess d^5 , in which the end j' of the extractor 60 enters when the breech-block is fully depressed, is so formed that the said extractor will be

70 moved toward the barrel when the said breech-block commences to rise. The said extractor is, moreover, formed with an inclined portion, j^2 , with which the inclined surface on the upper part of the breech-block will engage when the latter is raised, so that the said extractor, if not carried back to its normal position by the action of the recess d^5 on its end j' , will be fully 75 returned to its normal position by the said inclined surfaces without the assistance of an extra spring.

As the aforesaid connecting-rod m extends through the lower part of the space within which the breech-block slides, I provide for the 80 free movement of the said breech-block by forming an aperture, d^4 , in the lower part of the latter, so that the said connecting-rod will not obstruct or interfere with its movement.

The cock or hammer f , which strikes the firing-pin i to explode the cartridge in my improved fire-arm, is constructed as follows—that is to say: The striking-arm f' of the cock is preferably of rectangular form in transverse section, and from its striking-face is carried 85 backward and downward in a curved form, as shown, so as to permit it to pass freely through a slot provided for the purpose in the tail of the breech-shoe c . The said curved part may be fitted so closely within the said slot as to 90 prevent the entrance of dirt or foreign matter to the lock. Near the striking-face of the said cock a comb or projection, f^2 , is provided thereon to permit the operator to adjust the cock 95 without affecting or changing the position of the breech mechanism. The other end of the cock is so arranged that the ordinary V-shaped mainspring g and the swivel n may be used in connection therewith. It is provided with 100 notches or with a notched tumbler, o , formed in one piece with or separately from the said cock; and an important feature of this part of 105 my invention is the placing of the said tumbler at one side or out of the plane of the cock or hammer for the purpose of permitting the cock 110 to strike the firing-pin exactly in line with the axis of the barrel. I prefer to form the nose 115 or striking part of the said cock with a projection, f^* , which, when the piece is fired, enters a recess, d^* , formed in the breech-block below 120 the nipple, as shown in Fig. 1, in such a manner as to effectually prevent the said breech-block from being forced downward by the escape of gas from a defective cartridge, or otherwise. The arrangement of the said projection 125 for holding the cock below the nipple permits the cutting away of the upper part of the breech-block at d^* , and the arm is thereby conveniently adapted for the use of an ordinary snap-cap for the purpose of instruction or drill. The trigger h , forming part of my improved breech mechanism, is of the peculiar form shown.

In order to prevent the accidental displacement or falling of the breech-block, I in some cases fix a spring upon the breech-shoe c to 130 act upon the said breech-block or upon the tumbler k ; or a spring may be arranged in con-

nection with the outside or main lever, *l*, to prevent the falling of the said breech-block unless a considerable pressure should be applied to the said main lever. *d*² represents a slot, 5 which is formed in each side of the breech-block, and into which pins or studs on the breech-shoe are arranged to enter and act as stops to limit the movements of the said breech-block.

10 In Figs. 14, 15, and 16 I have shown other convenient means for retaining the breech-block in position for firing and preventing the accidental misplacement of the same. For this purpose I employ a lever or latch, *p*, mounted 15 on a pin, *p'*, within the breech-shoe *c*, at the lower rear portion thereof, as shown. The upper portion, *p*², of this lever is arranged to project through the rear surface of the aperture or space in which the breech-block *d* slides, so 20 that when the said block is in position for the firing of the piece the top of the said lever can be pressed forward underneath the block and into a recess in the same, as shown in Fig. 15, so that when in this position it will entirely 25 prevent the descent of the block.

The upper end of the lever or latch *p* is caused to fall forward to hold the breech-block, as shown in Figs. 14 and 15, by means of the pivoted breech-trigger *q*, which is acted on by 30 a spring, *q'*, to cause the forward toe, *q*², of said trigger to exert an upward pressure on the rearward-projecting toe *q*³ at the lower part of the lever or latch *p*. In order to disengage the lever *p* from engagement with the 35 breech-block, the breech-trigger is pressed upward toward the stock *b*, when the upper end of the lever *p* will be caused to fall rearwardly from the breech-block, either by means of a light spring, (not necessary to show,) which 40 acts to normally throw the upper end of the said lever rearwardly, or else by connecting the toe *q*² of the breech-block to the toe *q*³ on the lever.

Instead of forming the rod *m* with a slot, *m'*, 45 as hereinbefore described, I may modify the same by forming it with a hook or a projection, the surface of which will be nearly at right angles to the said rod, the said projection being arranged to work in the slot of the 50 tumbler, and be held in its position in the same by a pin or screw.

In Figs. 14, 15, and 16 I have shown the sliding bar or connecting-rod *m* provided with 55 projections *m*² at both ends, the inner surface of the said projections being at right angles, or nearly so, to the said rod. The object of this arrangement is to prevent the oscillation of the connecting rod.

I also in some cases modify the construction 60 of the breech-tumbler *c* by cutting a slot through the breech-block *d* and passing a pin or screw through the arms of the tumbler and the said slot; or I may fix pins in the breech-block and provide the arms of the tumbler with suitable 65 grooves or slots, within which the said pins will work.

It will be obvious from the above description that by means of the outside lever, *l*, which is connected with the parts as above described, and which has a flattened and roughened part, *l'*, at its free end, the breech-block *d*, the extractor *j*, and the cock or hammer *f* may be all conveniently and simultaneously operated.

By the arrangement of the parts according 75 to my said invention the lock mechanism may be protected from the foul matter which escapes from a defective cartridge, and from sand, dirt, or other foreign matter which might otherwise impede its action.

What I claim is—

1. The combination, in a fire-arm having the vertically-slidable breech-block *d*, of the lever *l*, arranged at the side of the gun, the tumbler *k*, fitted upon the spindle of the said lever and 85 engaging the slidable breech-block, the movable rod connecting the tumbler with the cock, and the extractor *j*, acted upon by the said tumbler, whereby the opening of the breech, the cocking of the gun, and the extraction of 90 the cartridge-shell will all be effected simultaneously by one downward movement of the lever, substantially as described.

2. The combination of the lever *l*, located at one side of the gun and provided with the 95 transverse spindle *l'*, the tumbler *k*, secured to said spindle, the cock *f*, having the front projection, *f*^{*}, a link-connection between the tumbler and cock, and a vertically-sliding breech-block, *d*, constructed with the recess *d*^{*}, said 100 members being constructed and arranged for operation substantially as described.

3. The combination of the tumbler *k*, mounted on the axis or spindle *l'*, and having the horns or projections *k*², the vertically-sliding 105 breech-block *d*, having the grooves *d*² in its sides, which engage the horns or projections of the tumbler for depressing the breech-block by the direct downward pressure of said horns or projections, and a cock or hammer connected by a rod with the said tumbler, said members being arranged to operate substantially as described.

4. The combination, with the cock, the extractor, and the vertically-slidable breech-block, of the breech-tumbler *k*, fitted upon the spindle of the operating-lever, and formed with the studs *k'* *k*² or projections upon the arms *k*² *k*³, the tubular transverse part *k*³, the arm *k*⁴, and a rod connecting the cock with the said 120 breech-tumbler, for the purpose described.

5. The combination, with the vertically-sliding breech-block, of the upright lever or latch *p*, pivoted at its lower end, and provided with a rearward-projecting toe, *q*³, and the pivoted 125 breech-trigger *q*, having a toe, *q*², and acted on by a spring, substantially as and for the purpose described.

WILLIAM SOPER.
